UNITED STATES PATENT OFFICE.

CLARENCE W. HUBBELL, OF NAUGATUCK, CONNECTICUT, ASSIGNOR TO THE GOODYEAR'S INDIA RUBBER GLOVE MANUFACTURING COMPANY, A CORPORATION OF CONNECTICUT.

BOOT.

1,349,572.

Specification of Letters Patent. Patented Aug. 17, 1920.

Application filed November 7, 1919. Serial No. 336,371.

To all whom it may concern:

Be it known that I, CLARENCE W. HUBBELL, a citizen of the United States, residing at Naugatuck, county of New Haven, 5 and State of Connecticut, have invented certain new and useful Improvements in Boots, of which the following is a full, clear, and exact description.

This invention relates to footwear and 10 especially to a waterproof boot provided with a skirt or extension suitable for hunters and fishermen.

Boots with skirt extensions as heretofore made have had no provision for adjusting 15 their foot portions tightly or snugly about the ankle and in consequence have permitted the foot to slip back and forth in an uncomfortable manner. The boot to which the skirt has been attached has had to be 20 large enough around the ankle to permit the last upon which it is built to be withdrawn and this fact together with the stiff and unyielding character of the materials constituting the boot are responsible for 25 the loose fitting of the article about the ankle of the wearer. This feature of construction renders the boots unsuitable for hunting and fishing purposes where considerable walking is inevitable in the quest for 30 game. Furthermore prior "hip" boots are heavier than necessary because of the weight and length of the stout upper which usually reaches to a point adjacent the knee.

The present invention aims to provide a 35 skirt-topped short boot free of objectionable looseness about the ankle, and a waterproof article that is more comfortable and lighter than those heretofore made but durable and stout enough to meet service requirements.

It consists essentially of a boot and skirt 40 united in a durable waterproof fashion and adjustable over the instep and around the ankle for conforming the upper to the arch and ankle of the wearer very much after 45 the fashion of an ordinary high shoe.

The invention is illustrated in the accompanying drawings in which:

Figure 1 is a perspective of the boot 50 ready to be laced up.

Fig. 2 is a plan view in horizontal section at the plane of the upper edges of the boot or foot portion proper.

Fig. 3 is an inside view of the pocket or

front closure before its application to the 55 last.

In the drawings the article is shown comprising a boot or shoe portion indicated generally by the numeral 1 and a skirt or extension 2. The boot or shoe portion includes a vamp 3 and quarters 4 which latter terminate in lacing flies 5. By a lacing 6 the flies 5 may be drawn together to snug the upper about the ankle of the wearer, water being excluded by a placket closure 65 or foldable member 7 which is united marginally to the vamp 3 and quarters 4 behind the eyleted flies 5. The quarters 4 and placket closure 7 together constitute a continuous or unbroken upper. It is to be 70 noted that the flies 5 terminate short of the upper edges of the quarters, as indicated at 5', and that the placket closure or foldable member 7 is united marginally to the quarters when it is in a folded flat condition, i. e., when the surfaces defining the 75 V-shaped openings 8 and 9 in Fig. 2 are directly in contact.

After the boot or shoe portion 1 has been completed, the skirt portion 2 preferably of 80 a single thickness of flexible rubber coated fabric reinforced if desired by an extra layer of rubberized fabric terminating on the line indicated at 2' has its lower edge adhered or "stitched" thereto as indicated 85 at 2''. While this may be done in any suitable manner it has been found convenient to spread or open the placket closure 7 while the boot or shoe is on the last, the skirt being brought from one side of the rear center 90 line around over the central median line of the placket closure held distended in any convenient manner as by a tapering or pointed tool, and afterward the last is turned over and the seaming continued 95 from the front center to the rear center of the boot. Then the longitudinal edges of the skirt are joined together at the rear by a single longitudinal lap seam. To hold the skirt up over the knee a strap 10 and buckle 100 11 are preferably provided for connection at the waistline of the wearer.

The article is preferably made of rubberized fabric and gum the shoe and placket closure being preferably heavy and stout 105 and the skirt light and flexible. The location of the placket closure at the front of the shoe insures a gathering of the fullness

in the skirt over the front portion of the leg where it is less likely to catch on obstructing brush and the like than if it were located at the sides of the leg. A single 5 placket closure or pocket member 7 at the front also enables the boot or shoe portion to be made blucher fashion which has heretofore not been attainable in waterproof footwear of the same kind as that to which 10 this invention relates and the placket member being of stout material like the adjacent quarters is not likely to tear or crack in walking when it is subjected to considerable flexure, but it is sufficiently yielding to 15 permit free and easy movement of the wearer.

It will thus be seen that I have provided a new and useful article of footwear which may be readily adjusted about the ankle so as 20 to minimize, if not eliminate, the liability of blistering the heel heretofore present in prior topped boots. It is also light enough to be comfortable in walking even considerable distances, little or no greater discomfort 25 being occasioned than with an ordinary high shoe or bootee.

It is also to be noted that the boot of the present invention laces tight over the instep and around the ankle and is made of a 30 strong material not likely to be snagged by underbrush. The ankle and lower part of the leg are protected and conform very closely to the sides of the wearer's foot so that the lower portion of the boot is small. 35 Furthermore the joining of the skirt or leg covering to the external upper edge of the shoe insures smoothness on the inside. The lap seam joining the shoe and skirt being located entirely above the ankle, there is no 40 opportunity for the thin flexible skirt to be chafed or cracked and thus ruin the boot more rapidly than the material deteriorates in the usual course.

Having thus described my invention what 45 I claim and desire to protect by Letters Patent is:

1. As an article of manufacture, a boot

having foot and leg covering portions, the foot portion being provided externally with fastening devices for adjustment over the 50 instep and around the ankle, the foot and leg covering portions being united intermediate the ankle and knee by an endless substantially circular lap joint located entirely above the ankle, and a waterproof 55 rubber coating over the exterior of the article.

2. As an article of manufacture, a boot having a foot portion and a skirt extending up over the leg, the foot portion having a 60 continuous tubular upper formed by quarters joined together at the front by a foldable placket member covering the instep and the lower portion of the leg immediately adjacent the ankle, lacing flies on said foot portion at the junctions of said quarters and placket member, the skirt being continuous or tubular and having only a single longitudinal lap seam, the foot portion being made of reinforced material and the skirt be- 65 ing made of more flexible material than the foot portion. 70

3. As an article of manufacture, a reinforced high shoe having an upper with a front placket member adjustable over the 75 instep and around the leg and terminating immediately above the ankle, and a leg covering secured to the top of the quarters and placket member of the high shoe by a circumferential lap joint, the leg covering 80 being of lighter material than the high shoe and both being externally waterproofed.

4. As an article of manufacture, a waterproof Blucher shoe covering the foot and leg to a point immediately above the ankle and 85 adjustable over the instep and around the leg, and a waterproof leg covering lapping the upper edge of the shoe externally at a point entirely above the ankle where the lap joint is not subjected to flexure in walking. 90

Signed at Naugatuck, Conn., this 22nd day of October, 1919.

CLARENCE W. HUBBELL.
